UNITED STATES PATENT OFFICE.

ISAAC H. CONGDON, OF OMAHA, NEBRASKA.

FREIGHT-CAR.

SPECIFICATION forming part of Letters Patent No. 315,600, dated April 14, 1885.

Application filed February 9, 1885. (No model.)

To all whom it may concern:

Be it known that I, ISAAC H. CONGDON, a citizen of the United States, residing at Omaha, in the county of Douglas and State of Nebraska, have invented certain new and useful Improvements in Freight-Cars, of which the following is a specification, reference being had therein to the accompanying drawings.

This invention has relation to that class of freight-cars in which side boards are carried up from the car-floor and supported by stakes secured to side sills by loops of iron or by stake-pockets, and form a box wherein coal, sand, minerals, &c., are retained while being transported from place to place; and the object of the invention is to provide such an arrangement of braces or supports for the side stakes as to make it possible to use side boards of any required height, and prevent them from spreading outwardly at the top by the increased weight, while at the same time relieving the side sills from all twist and tendency to turn over, and still allowing the use of end-gates. The box is also free from all cross-ties, rods, &c., or any other obstructions which might impair its usefulness in carrying lumber or similar kinds of merchandise.

In the drawings, Figure 1 is a half side elevation and half longitudinal section of a car constructed in accordance with my invention. Fig. 2 is a plan of the same, one half showing the finished car and the other half its framing. Fig. 3 is a cross-section on line xx of Fig. 1. Fig. 4 is a perspective view showing the under side of one-half of the car.

It is well known that in cars of this class, with side boards as at present stayed, there is a tendency and a liability to cause said boards to be pressed outward at top and to twist and turn over the side sills. The stakes secured to the side sills by iron loops or stake-pockets act as levers with the loop or stake-pocket as a fulcrum, and the long end being four to six or more times the length of the shorter, an immense strain is brought on the lower end of the stakes and side sills, which soon split, bend, and break the stakes, or if too strong to be broken they indent and sink into the sills. The nuts securing the loops of iron or stake-pockets also partially or wholly embed themselves in the inside of the sills. From these and other causes the stakes soon become separated

from the sills at the fulcrum-point and the stakes lean outwardly. The weakness of this construction is felt more and more, as the carrying tonnage of cars is now greatly increased without a corresponding increase in the length and width of the car-frame. It is therefore necessary to make the side boards much higher, and, as previously explained, this greatly increases the twisting strain on the sills, which are now only stayed transversely by means of flooring spiked thereto. To overcome these objections it is necessary to so brace the side stakes as to relieve the side sills from this twisting strain, while at the same time the box remains free from obstructions. The arrangement of bracing is also simple and cheaply made, and capable of being applied to cars in use. With the object of overcoming these defects stated many cars have been made wherein the end boards are stationary and not suited to act as movable gates, and the tie-rods are carried across the car from the top of one stake to the other. This construction unfits the car for use in the transportation of lumber and similar merchandise.

In my construction the framing of the car is composed of the side sills, A, center sills, B, and the end sills, C, that unite them, and these, as well as the tie-planks D and flooring E, are of the usual construction.

Upon the flooring E are placed the side boards, F, and end-gates G.

Secured to the side sills, A, by iron staples or loops h are the stakes I and I', supporting the side boards, F, against inward thrust.

Bolted to the under side of the sills of the car are cross-pieces d, similar to the tie-planks D. They are arranged at points transversely in line with the side stakes, I', and the latter, in place of stopping at the lower edge of side sills, as heretofore, are carried down over the ends of the tie-planks D and of the supplementary tie-planks d. In this manner the side sills are relieved from all twist and strain and liability to turn over under the side pressure of the load within the box, and said pressure is transferred to the ends of the tie-planks D and supplementary tie-planks d, against which the strain is equalized, as the weight from one side of the car is counterbalanced by the weight at the other side exerting an equal pressure on the tie-planks. The

strain on the stakes is also greatly lessened, as their length above and below the fulcrum-point is much nearer the same.

From Fig. 4 it will be seen that the supplementary tie-planks *d*' are stopped at the draw-timbers *L*, and cut out at *M* for the free rotation of the wheels.

In place of the iron loops or stake-pockets, cross-bolts of round iron, *O*, are substituted to retain alternate pairs of stakes in position. The cross-bolts are located just above the sills, the under side of the flooring being grooved to receive said bolts. They pass through the stakes at the sides of car, and are secured by nuts and washers. This arrangement of cross-bolts may be used for every stake, and thus still more equalize the strain on the stakes, as the fulcrum-point is more nearly central.

In cars where the side sills are very deep it 20 may not be necessary to put in supplementary tie-planks *d*, but only to extend the center stakes down over the tie-planks *D*. This arrangement of stake-supports permits the end-gates *G* to be hinged close to the floor, and be 25 retained in an inclined position by the cleats *J*, and dispense with end stakes.

The liability of the side boards to bulge outward, as heretofore braced, made the use of end stakes, and consequently the standing of 30 end-gates perpendicular, almost imperative,

and as it is necessary to remove these stakes when loading cars with lumber, &c., a great many of them are lost.

Having now fully described my invention, what I claim, and desire to secure by Letters Patent, is—

1. The combination of the sills and tie-planks *D* with the side stakes, *I*, extending over the ends of said tie-planks, substantially as and for the purpose described. 40

2. The combination of the sills, the tie-planks *D*, and the supplementary tie-planks *d*, with the side stakes extending over the ends of said supplementary tie-planks, substantially as and for the purpose described. 45

3. The combination of the sills and the side stakes with the cross-rods *O*, passing through said stakes and across all the sills, substantially as and for the purpose described.

4. The combination of the sills, the tie-planks *D*, supplementary tie-planks *d*, stakes *I* and *I'*, extending over the ends of said planks, and the cross-rods *O*, substantially as and for the purpose described. 50

In testimony whereof I affix my signature in presence of two witnesses.

ISAAC H. CONGDON.
